UNITED STATES PATENT OFFICE

RICHARD S. GIESE, OF SEWICKLEY HEIGHTS TOWNSHIP, PENNSYLVANIA

DESIGN FOR A GOBLET OR SIMILAR ARTICLE

Application filed April 5, 1930. Serial No. 35,174. Term of patent 3½ years.

To all whom it may concern:

Be it known that I, RICHARD S. GIESE, a citizen of the United States, residing in Sewickley Heights Township, in the county of Allegheny and State of Pennsylvania, have invented a new, original, and ornamental Design for a Goblet or Similar Article, of which the following is a specification, reference being had to the accompanying drawing, forming part thereof.

The figure is a view in side elevation of a goblet showing my new design, the bowl portion being shown in dotted lines.

I claim:

The ornamental design for a goblet or similar article as shown and described.

RICHARD S. GIESE.
